UNITED STATES PATENT OFFICE.

JAMES P. FEGAN, OF CAMBRIDGE, MASSACHUSETTS, ASSIGNOR TO GEORGE H. SALLAWAY, OF SOMERVILLE, MASSACHUSETTS.

DESIGN FOR A GRIP-BRACKET.

SPECIFICATION forming part of Design No. 25,670, dated June 23, 1896.

Application filed May 18, 1896. Serial No. 592,069. Term of patent 14 years.

To all whom it may concern:

Be it known that I, JAMES P. FEGAN, of Cambridge, in the county of Middlesex and State of Massachusetts, have invented and 5 produced a new and original Design for Grip-Brackets, of which the following is a specification, reference being had to the accompanying drawing, forming a part hereof.

In the drawing the figure is a perspective 10 view of a bracket embodying my design.

The essential feature of my design consists 15 in a rectangular plate having a rectangular central opening, a boss projecting from the plate at one side of the opening, and a headed pin projecting laterally from the apex of the boss and parallel with the plane of the plate.

a represents the rectangular plate, having a substantially rectangular central opening *b*, provided with rounded corners.

c is the boss rising from the plate at one 20 side of the opening, said boss being flat on the inner side and rounded on the outer side, and *d* represents a pin having a head *d'* and extending from the flat side of the boss *c* in a direction parallel with the plane of the plate *a*. 25

I claim—

The design for a grip-bracket substantially as shown and described.

In testimony whereof I have signed my name to this specification, in the presence of 30 two subscribing witnesses, this 12th day of May, A. D. 1896.

JAMES P. FEGAN.

Witnesses:

A. D. HARRISON,
P. W. PEZZETTI.
